(57) **CLAIM**

The ornamental design for an outdoor lighting fixture, as shown and described.

DESCRIPTION

FIG. 1 is a perspective view of an outdoor lighting fixture according to my new design.

FIG. 2 is a top plan view thereof.

FIG. 3 is a side elevational view thereof, all sides being mirror images; and,

FIG. 4 is a bottom plan view thereof.

The broken lines in the figures form no part of the claimed design.

1 Claim, 4 Drawing Sheets
